UNITED STATES PATENT OFFICE.

IDA M. SHACKLE, OF WATERTOWN, SOUTH DAKOTA.

COVER-FASTENER.

1,308,962.

Specification of Letters Patent.

Patented July 8, 1919.

Application filed July 27, 1917. Serial No. 183,125.

To all whom it may concern:

Be it known that I, IDA M. SHACKLE, a citizen of the United States, residing at Watertown, in the county of Codington and 5 State of South Dakota, have invented certain new and useful Improvements in Cover-Fasteners; and I do hereby declare the following to be a full, clear, and exact description of the invention, such as will enable 10 others skilled in the art to which it appertains to make and use the same.

This invention relates to improvements in a cover fastener and has for one of its objects the provision of a device of this character, whereby the covers upon a bed may 15 be secured over the occupant to the bed to prevent the occupant from becoming uncovered.

Another object of this invention is the 20 provision of a pair of clamps connected together and one of said clamps adapted to receive the covering of the bed and the other clamp to receive the bed so that the covering will be kept from being removed by the 25 occupant.

A further object of this invention is the 30 provision of means for adjusting the clamps toward and from each other so as to compensate for different lengths of covering upon the bed.

A still further object of this invention is 35 the provision of a cover fastener of the above stated character, which shall be simple, durable and efficient, and which may be manufactured and sold at a comparatively low cost.

With these and other objects in view, as 40 will become more apparent as the description proceeds, the invention consists in certain novel features of construction, combination and arrangement of parts as will be hereinafter more fully described and claimed.

For a complete understanding of my 45 invention, reference is to be had to the following description and accompanying drawing, in which:

Figure 1 is a side elevation of a cover fastener illustrating it applied to a bed, 50 Fig. 2 is a longitudinal sectional view of the same,

Fig. 3 is a transverse sectional view taken through one of the clamps,

Fig. 4 is a plan view of one of the con-

necting members for connecting the clamps 55 together.

Referring in detail to the drawing, the numeral 1 indicates connecting members, which are of substantially T-shape formation and having their stem or leg portions 60 screw-threaded to receive a turn buckle 2 for adjusting the connecting members toward and from each other.

Clamps 3 consist of body portions 4, which have one of their ends bent inwardly to 65 form teeth 5, while their opposite ends are bent outwardly to form finger grips 6. The body portions 4 have formed thereon, ears 7, which are apertured to receive the heads 8 upon the T-shape connecting members 1, 70 whereby the sections of the clamps are pivotally connected together. Coiled springs 9 are positioned upon the heads of the T-shaped members 1 and have one of their ends twisted about the leg or stem portions 75 of the T-shape members as illustrated at 10, while their opposite ends are bent to form arms 11 that engage the under faces of the finger grips 6 for normally urging the teeth 5 into engagement with each other. 80

In operation, one of the clamps is secured to the bed covering 12 as shown in Fig. 1, while the other clamp is secured to the head 13 of the bed 14, whereby the cover 12 is held over the occupant of the bed. 85

From the foregoing description taken in connection with the accompanying drawing, it will be noted that a device has been provided, which is capable of holding the bed covering over a child, and which will prevent the child from kicking or disposing of the bed covering. 90

While I have shown and described the preferred embodiment of my invention, it will be understood that minor changes in 95 construction, combination and arrangement of parts may be made without departing from the spirit and scope of the invention as claimed.

Having thus described my invention, what 100 I claim is:

A cover fastener comprising a pair of companion members having one of their ends bent to form gripping teeth and their ends bent angularly to form finger grips, 105 inwardly directed apertured ears formed on said members and arranged in overlapping pairs, a T-shaped member having its head

portion extending through the apertures in said ears, and a spring wound about said head and leg portion of the T-shaped member and having its ends disposed against the
5 finger grips for forcing the gripping ends of said members in engagement with each other.

In testimony whereof I affix my signature in presence of two witnesses.

IDA M. SHACKLE.

Witnesses:

ADELINE SHACKLE,
Mrs. A. SPINNER.
